UNITED STATES PATENT OFFICE.

LOUIS A. CASGRAIN, OF BEVERLY, MASSACHUSETTS, ASSIGNOR TO UNITED SHOE MACHINERY COMPANY, OF PATERSON, NEW JERSEY, A CORPORATION OF NEW JERSEY.

WORK-GAGE.

1,048,295.

Specification of Letters Patent. Patented Dec. 24, 1912.

Original application filed March 17, 1906, Serial No. 306,612. Divided and this application filed May 21, 1907. Serial No. 374,852.

To all whom it may concern:

Be it known that I, LOUIS A. CASGRAIN, a citizen of the United States, residing at Beverly, in the county of Essex and Commonwealth of Massachusetts, have invented certain Improvements in Work-Gages, of which the following description, in connection with the accompanying drawings, is a specification, like reference characters on the drawings indicating like parts in the several figures.

This invention relates to work gages such as are used in a large variety of machines, including nailing machines, slugging machines and pegging machines, for determining the position of the work being operated upon with reference to the operating devices or tools.

The specific form of gage herein shown and described is particularly designed for use in connection with the machine for inserting fastenings shown and described in application for Letters Patent of the United States, Serial No. 306,612, filed by this applicant March 17, 1906, of which the present application is a division.

One of the objects of the present invention is to provide a work gage comprising a member for engaging the work which is movable with relation to the parts of the machine which operate upon the work but which will be locked or securely held in any position to which it may be moved.

In the preferred form of the invention, the means for locking the work engaging member in position comprises a plurality of locking devices such, for example, as a pair of roller clutches or clamps which act normally to prevent movement of the work engaging member and means, herein shown as a manually operable member, is provided for first unlocking the work engaging member and then moving it to another position.

As herein shown, while the work engaging member is free to move in one direction it is still locked against movement in the opposite direction and whenever the means for unlocking the work engaging member becomes inoperative the locking means automatically becomes operative so that, as above explained, the work engaging member will be held firmly in place not only in a limited number of predetermined positions but in

any and all positions which it may take, no separate manually operated locking means being required.

In machines for inserting fastenings, it is often desirable to insert the fastenings in two or more rows and hence another object of the present invention is to provide a work gage which may be quickly and readily moved from one to another predetermined position so that rows of fastenings, for example, may be inserted at a predetermined distance from each other and from the edge of the sole of a shoe or other work.

Accordingly in another aspect, the invention comprises a manually operable means, such, for example, as a hand lever, through which the work engaging member may be moved and coöperating stop devices for predetermining at least three positions of the work engaging member. Preferably these parts are so arranged that the work engaging member may be moved from one predetermined position to any one of a plurality of other predetermined positions by a single movement of the manually operable means.

In addition to the elements of novelty already specifically mentioned, the present invention also comprises certain arrangements and combinations of parts as well as details of construction which will be hereinafter fully described and defined in the appended claims.

Referring to the drawings,—Figure 1 shows, chiefly in side elevation but partly in section, a preferred embodiment of the work gage which constitutes the present invention, together with certain parts of a machine of which it forms a part and a portion of a shoe upon which the machine is adapted to operate; Fig. 2 is a plan view, upon a somewhat larger scale, of the work gage shown in Fig. 1 with certain of the parts cut away.

As herein shown, the gage is applied to the machine fully described and illustrated in co-pending application Serial No. 306,612, above referred to, the same parts being designated by the same reference characters in the two applications. It will be understood, however, that the work gage of the present application, while shown as used in connection with the machine of the earlier application, may be, without sub-

stantial change, applied to many other machines in which it is desired to have a work gage.

The reference numeral 2 represents a part 5 of the frame of the machine. The work, shown as a portion of a shoe, is clamped between the work support or horn 30 and the presser foot 93. The edge of the sole is engaged by a member 230 of the work gage, 10 shown as a wheel or disk provided with a roughened or serrated periphery and rotatably supported upon a bar or slide 238 by a stud 239, the slide being movable longitudinally in the supporting arm or bracket 15 240.

As fully explained in the original application above mentioned, mechanism may be provided for rotating the work engaging member 230 in order to feed the work. As 20 herein shown, this mechanism includes a lever 241 actuated from the main shaft of the machine which is adjustably connected to the work engaging member 230 by a link 246. According to the invention herein 25 claimed, however, it is immaterial whether or not the work engaging member serves simply as a gage or whether it also forms part of the means for feeding the work. The work engaging member may comprise 30 merely a freely rotatable wheel or roll, the end of a bar such as bar 238, or any other suitable device adapted to bear against some part of the work.

The specific mechanism, illustrated, for 35 adjusting the work gage and for locking it in adjusted position will now be described. The bar 238 is cut away on one side for about half of its width to receive a clutch block 250 which is adjustably connected to 40 the bar by a thumb screw 251, a spring 251' being interposed between the bar and block to take up any backlash. The clutch block 250 is also cut away on one side and has two oppositely inclined surfaces 255. A 45 clutching roll 256 is interposed between each of the inclined surfaces and the adjacent wear plate 257 forming part of the wall of the slot or opening in lever 240 and is normally forced by a spring 258 into the narrower 50 end of the tapering space formed between said surface and plate. The block 250, the bar 238, and the wheel 230 are thus locked by the clutching rolls 256 in any position whatever to which they may be moved. 55 Each of the rolls may be moved toward the wider end of the tapering space in which it lies, when it is desired to adjust the gage, by one of two pins 259 slidable in block 250 and in position to be engaged by one end of 60 a lever 260 pivoted upon an extension 261 of lever 240. The end of lever 260 passes through a slot 262 in the side of the enlarged end of lever 240 in which the bar 238 and clutch block 250 slide and extends 65 into a pocket in the block between the ad-

jacent ends of pins 259. When lever 260 is moved in either direction its end first engages one of the pins 259 and releases the corresponding clutching roll 256, as described and then, as it is moved farther, the end 70 engages the side wall of the pocket in which it lies and carries with it the block 250 and, therefore, the work engaging member 230. When the movement of the lever is stopped the released clutching roll 256 is again 75 moved by its spring 258 into locking position and the gage is then held firmly in its new position.

It will be noted that, after the screw 251 has been adjusted as desired and while the 80 machine is in operation, the clutch block 250 is positively connected to the bar 238 and therefore is, in effect, an integral part of the bar so far as the operation of the work gage is concerned and indeed, if the provision of 85 this adjustment through the screw 251 is not desired, the block 250 may in fact form an integral part of the bar 238.

In many classes of machines, it is often 90 desirable, as above explained, to move the gage quickly into any one of two or more predetermined positions, thereby varying correspondingly the distance from the edge of the work at which fastenings will be inserted. To this end, the lever 260 has on 95 one arm a projection 263 provided with a recess 264. This projection is held by a spring 265 in engagement with a cam surface of a T-shaped lever 267 pivoted on the extension 261 of lever 240. As illustrated, 100 this cam surface is made up of two outwardly-inclined surfaces 268, which meet in an edge adapted to rest in the recess 264. When the lever 267 is in this central position the gage wheel 230 is in its forward 105 position, so that the fastenings will be inserted nearest the edge of the work. If the operator wishes to retract the gage, he moves lever 267 from its central position. The co-operation of the projection 263 with one of 110 the surfaces 268 permits lever 260 to be moved by its spring 265. This movement is limited by the engagement of one of two adjustable stop screws 269 in the head of lever 267 with a fixed stop 270 on extension 261. 115 If the two inclined surfaces, the two co-operating sides of projection 263, and the adjustment of the two screws 269, are all respectively alike, as shown, then the gage will be retracted substantially the same distance when lever 267 is moved to both extreme positions. However, the stop screws 269 may be adjusted to vary the positions that the gage will take when the lever 267 is moved in either direction laterally from 120 its central position, thus giving three predetermined positions to which the gage may be quickly and readily moved. A similar result would be accomplished by making the two surfaces 268 of different shape. More- 125 130

over, as above described, the gage may be independently adjusted by rotation of thumb screw 251.

The lever or arm 240 is supported so that 5 the gage may be adjusted vertically. For this purpose, the rear end of the lever is provided with a "three point bearing." The lever has two similar feet 274. The toe 275 of each foot bears directly against a part of 10 the machine frame while through the web 276, which connects the feet, passes an adjusting screw 277 bearing against another part of the frame. A headed screw 278, passing somewhat loosely through a part of 15 the frame 2, is threaded into each foot, serving to clamp the foot of the lever firmly to the frame. Hence the height of the gage may be regulated by loosening screws 278, if necessary, adjusting screw 277 and then 20 tightening up screws 278.

It is believed that the manner of operating the work gage has already been set forth fully and clearly in the description of its various parts. The scope of the invention, 25 also, has been indicated and will also be found defined in the claims.

Having thus described my invention in detail, what I claim as new and desire to secure by Letters Patent of the United 30 States is:—

1. In a machine of the class described, the combination with a work gage comprising a work engaging member movable to change the position of work, of means for positively 35 locking it in any position to which it may be moved, and means for unlocking said member and for thereafter engaging a part fixed relatively to said member for moving it to a new position.

2. In a machine of the class described, 40 having fastening inserting and work supporting mechanism, the combination of means for locating the edge of the work at any desired distance from the line in which fastenings are to be inserted comprising a work engaging member, means for locking it in position, and means for first unlocking said member and thereafter directly engaging a part fixed relatively to said member 45 and moving it to another position, said locking means becoming operative automatically whenever the unlocking means becomes inoperative.

3. A work gage comprising a work engaging member movable to change the position of work, a carrier rigidly connected with 55 said member, locking means acting normally to prevent movement of said carrier, and means for first releasing the locking means 60 and thereafter directly engaging a fixed part of the carrier for moving said member to a new position.

4. A work gage comprising a work engaging member movable to change the position 65 of work, a recessed carrier rigidly connected

with said member, a plurality of roller clutches acting normally to prevent movement of said carrier, and movable means extending into a recess in the carrier constructed and arranged first to release a 70 clutch and thereafter to directly engage a fixed part of said carrier for moving the work engaging member into a new position.

5. A work gage comprising a fixed guide, a slide rectilinearly movable therein, a work 75 engaging member carried by the slide, a plurality of locking devices to lock the slide rigidly to the guide, and a lever for releasing either device and for moving the said member either forwardly or backwardly. 80

6. A work gage comprising a fixed guide, a slide movable therein, a work engaging member carried by and rigid with the slide, a plurality of roller clutches to lock the slide rigidly to the guide, and a device located 85 between the clutches constructed and arranged so that when moved in either direction it will first release one of the clutches and thereafter directly engage a part rigid with the slide and move the work engaging 90 member to a new position.

7. A work gage comprising a slide, a work engaging member carried by and rigid with the slide, a support in which the slide is guided, a pair of roller clutches acting normally to lock the slide rigidly to its support or guide, and a lever movable in opposite directions first to release one or the other of the clutches and thereafter to directly engage a part rigid with the slide to change 95 the position of the work engaging member.

8. In a machine for inserting fastenings, the combination of means for locating the edge of the work at any desired distance from a line in which fastenings are to be inserted comprising a work-engaging member, independent means for locking it against movement in opposite directions, manually operable means including a lever provided with adjustable stops through which said 100 member may be moved, and relatively stationary stops coöperating with the movable stops for predetermining certain positions of said member.

9. In a machine for inserting fastenings, 115 the combination of means for locating the edge of the work at any desired distance from a line in which fastenings are to be inserted comprising a work engaging member, manually operable means including a lever 120 provided with adjustable stops through which said member may be moved, and relatively stationary stops coöperating with the movable stops for predetermining certain positions of said member.

10. A work gage comprising a work engaging member movable to change the position of work, a lever through which it may be moved, manually operable means for actuating said lever, and coöperating stop de- 130

5 vices for predetermining three positions of said member, the stop devices for predetermining one of said positions being located upon adjacent surfaces of said lever and 5 manually operable means.

11. A work gage comprising a work engaging member, a lever through which it may be moved, and a manually controlled self-locking lever coöperating with the first- 10 mentioned lever and constructed to carry the work engaging member from one predetermined position to any one of a plurality of other predetermined positions by a single movement.

15 12. A work gage comprising a work engaging member, a lever through which it may be moved, independently supported manually controlled means coöperating with the lever for moving the work engaging 20 member to any one of three predetermined positions, and adjusting means for varying each of such positions.

13. A work gage comprising a work engaging member, a lever through which it 25 may be moved, a manually operable lever, said levers having coöperating relatively movable cam surfaces by which the positions of the work engaging member are determined.

30 14. A machine frame and a work gage supported thereon comprising a work engaging member, a supporting arm or bracket provided with three separate bearing points to engage the frame, and means 35 for securing it rigidly to the frame, including means for adjusting it so as to vary the position vertically of the work engaging member.

15. A work gage comprising a work engaging member, a lever through which it 40 may be moved, a manually operable lever, said levers having coöperating relatively movable cam surfaces by which two positions of the work engaging member are determined, and one of said levers having a 45 notch and the other a coöperating projection located between said cam surfaces by which the third position of said member is determined.

50 16. A work gage comprising a work en-

gaging member, a lever through which it may be moved, a manually operable lever, said levers having coöperating relatively movable cam surfaces by which two positions of the work engaging member are determined, and one of said levers having a notch and the other a coöperating projection located between said cam surfaces by which the third position of said member is determined, and adjustable coöperative stop devices for varying the position of said 55 manually operable lever.

17. A device of the class described comprising a fixed member provided with a guide, a slide arranged for rectilinear movement in the guide and carrying a work engaging member, a plurality of locking devices to lock the slide rigidly to the guide, and a lever for releasing either device and for thereafter directly engaging said slide 60 and moving said member either forwardly or backwardly.

18. A device of the class described comprising a fixed member provided with a guide, a slide arranged for movement in the 75 guide and carrying a work-engaging member, a locking device to lock the slide rigidly to the guide, and a lever for releasing the locking device and for thereafter engaging a portion of said slide in line with said device and moving said member to a different 80 position.

19. A work gage comprising a work engaging member, a lever having connection with said member, a spring acting on said 85 lever to effect a normal retraction of said member and a manually controlled lever provided with adjustable stop devices and arranged to be positioned for variably controlling the amount of movement imparted 90 to the work engaging member by said spring.

In testimony whereof I have signed my name to this specification in the presence of two subscribing witnesses.
